UNITED STATES PATENT OFFICE.

RALPH WAGGONER, OF LOS ANGELES, CALIFORNIA, ASSIGNOR TO MARBELITE CORPORATION OF AMERICA, OF LOS ANGELES, CALIFORNIA, A CORPORATION OF DELAWARE.

DESIGN FOR A PEDESTAL.

Application filed February 13, 1928. Serial No. 25,431. Term of patent 14 years.

To all whom it may concern:

Be it known that I, RALPH WAGGONER, a citizen of the United States, residing at Los Angeles, in the county of Los Angeles and State of California, have invented a new, original and ornamental Design for a Pedestal, of which the following is a specification, reference being had to the accompanying drawing, forming a part hereof.

I claim:

An ornamental design for a pedestal, substantially as shown.

Signed at Los Angeles, California this 7th day of February, 1928.

RALPH WAGGONER.
